UNITED STATES PATENT OFFICE.

GEORGE P. CLEMENTS, OF NEW MILFORD, PENNSYLVANIA, ASSIGNOR OF
ONE-HALF TO JOHN C. McCONNELL, OF SAME PLACE.

SASH-HOLDER.

SPECIFICATION forming part of Letters Patent No. 293,310, dated February 12, 1884.

Application filed October 31, 1883. (No model.)

To all whom it may concern:

Be it known that I, GEORGE P. CLEMENTS, a citizen of the United States, residing at New Milford, in the county of Susquehanna and 5 State of Pennsylvania, have invented certain new and useful Improvements in Sash-Fasteners; and I do hereby declare the following to be a full, clear, and exact description of the invention, such as will enable others skilled 10 in the art to which it appertains to make and use the same.

My invention relates to certain improvements in sash-fasteners, and is more especially adapted to car-windows, though it can be used 15 on windows of any kind. It is so constructed that all rattling and jarring is prevented; and it consists of a metal slide secured to the window-sash and working on a bead or strip fastened to the window-frame, the slide being 20 provided with a set-screw for adjusting the window at any desired point, the knob of which set-screw is also used to raise and lower the window, all of which I will now proceed more particularly to point out and describe, 25 reference being had to the accompanying drawings, in which—

Figure 1 is a perspective. Fig. 2 is a vertical section taken through the center of the screw. Fig. 3 is a perspective of the slide 30 removed from the window.

Referring to said drawings, A is the window-frame, B the window-sash. C is a metal slide attached to the lower part of the sash by the screws f, and is provided with a slot, c. 35 D is a strip or bead secured to the window-

frame by the screws d, and fitting in the slot e of the slide C. Said slide C works on the bead D. E is a set-screw working in the slide C, and, binding against the bead D, serves to hold the sash at the position of adjustment. Said 40 screw is provided with a knob, e, which is used to tighten or loosen the screw, and to raise or lower window.

The operation of my fastener is as follows: By turning the knob to the left, the set-screw 45 is loosened from contact with the bead D, and the window can be raised or lowered to the desired position. Then, turning the knob to the right, it binds against the bead D and holds the window firmly in place, thus preventing any rattling or jarring.

This sash-fastener is very effective, can be made cheaply, and is so simple in construction that it is almost impossible for it to get out of order.

Having thus fully described my invention, I claim as new and desire to secure by Letters Patent—

In a sash-fastener, the slide C, secured to the window-sash, and having the slot c and set-screw E, in combination with the bead D, secured to the window-frame, substantially as and for the purpose shown and described.

In testimony whereof I affix my signature in presence of two witnesses.

GEORGE P. CLEMENTS.
